UNITED STATES PATENT OFFICE.

THOMAS E. BRALEY, OF WICHITA, KANSAS.

ROTARY EXPLOSIVE ENGINE.

Application filed December 8, 1923. Serial No. 679,353.

My invention relates to improvements in rotary explosive engines. One of the objects of my invention is to provide in an engine of the kind described having a rotary crank shaft, a rotor member having pistons reciprocative in cylinders provided in the rotary member, of novel means for transmitting rotation from the crank shaft to the rotor member.

10 A further object of my invention is the provision of novel means by which rotation of the rotor member is effected in a direction reverse the direction of rotation of the crank shaft, whereby the effect of torque due to the 15 rotation of the rotary member is counteracted.

Another object of my invention comprises a novel arrangement of the cylinders in the rotor member, whereby a central direct 20 thrust is obtained between the pistons and the cranks of the crank shaft.

A further object of my invention is the provision in an engine having radial cylinders in different paths of rotation, of ignition means arranged to fire the charges centrally in the respective cylinders, and in the same plane transverse to the planes of rotation of the cylinders.

25 A further object of my invention is to provide novel means for air cooling the cylinders.

Still another object of my invention is the provision in an engine of the kind described, of a constriction which is simple, relatively 30 cheap to make, strong and durable, not liable to get out of order, which operates with a minimum of friction, is compact, and which has a maximum of efficiency.

A further object of my invention is the 35 provision of a rotor member having cylinders provided with open outer ends arranged to be closed by the casing in which the rotor member revolves.

Still another object of my invention is the 40 provision of novel means for effecting non-leaking joints between the cylinders of the rotor member and the casing in which the latter revolves.

The novel features of my invention are 45 hereinafter fully described and claimed.

In the accompanying drawings, which illustrate the preferred embodiment of my invention,

Fig. 1 is an elevation looking at one end 50 of my improved engine.

Fig. 2 is an elevation looking at the opposite end thereof.

Fig. 3 is an enlarged central vertical section of the same.

Fig. 4 is a section on the line 4—4 of 60 Fig. 3.

Fig. 5 is a plan view, partly broken away, of the rotor member.

Similar reference characters designate 65 similar parts in the different views.

1 designates the body of the engine comprising a casing member having a circular periphery of which has an intake port 2 and an exhaust port 3, with which respectively communicate a fuel pipe 4 and an exhaust 70 pipe 5. If desired, the function of the pipes 4 and 5 and their respective ports may be reversed, in which case, the port 3 would be the intake port and the port 2 the exhaust port.

75 Fastened respectively to opposite ends of the body 1 are two brackets 6 and 7, in which is mounted a rotary crank shaft 8, having equal radially spaced cranks 9, 10, 11 and 12, respectively in different planes of 80 rotation. The shaft 8 may have the usual fly wheel, not shown.

A rotor member mounted in the body 1 has a central hub 13 rotatable on the shaft 8 and from which extend equally spaced radial 85 cylinders 14, 15, 16 and 17, in the planes respectively of rotation of the cranks 9, 10, 11 and 12. The rotor member has a circular rim 18, rotatably fitted in the body 1. The cylinders have open outer ends arranged 90 to be closed by the inner periphery of the body 1 excepting during the times that the cylinders communicate with the ports 2 and 3.

Respectively reciprocative in the cylinders 14, 15, 16 and 17 are pistons 19, 20, 21, and 22, respectively connected in the usual manner by connecting rods 23, 24, 25 and 26, to the cranks 9, 10, 11 and 12.

In order that each charge in each cylinder 100 may be ignited in the central plane of rotation of the cylinder containing it, the body 1, as shown in Fig. 3, has ignition openings 27, 28, 29 and 30, arranged in the same transverse plane, preferably centrally intermediate of the ports 2 and 3, and respectively in the central planes of rotation of the cylinders 14, 15, 16 and 17, and respectively communicating therewith during each rotation 105 of the rotor member.

In the said ignition openings 27, 28, 29 and 30, are suitable ignition devices, such as spark plugs 31, 32, 33 and 34. The timing mechanism, not shown, may be of any ordinary type, arranged to effect the operation of the spark plugs when the cylinders respectively align therewith. As each spark plug is in the central plane of revolution of the cylinder with which it cooperates, reliable firing of the charges is effected and a maximum of advance or retardation of the firing sparks is obtained.

As the ignition openings are located in the same transverse plane, which is parallel with the axis of rotation, of the rotor member, the same charge compressing and exploding effect is obtained in all of the cylinders.

Means is provided for transmitting rotation from the crank shaft 8 to the rotor member. Such means preferably provides for the rotation of the rotor member in a direction opposite to the direction of rotation of the crank shaft, whereby the torque, due to rotation of the rotor member, is counteracted.

The means for transmitting rotation from the crank shaft to the rotor member may comprise the following described mechanism.

Rigidly secured to the crank shaft 8, Fig. 3, is a bevel gear wheel 35, which meshes with two diametrically opposite intermediate bevel gear wheels 36 and 37, which are respectively rotatable on alined studs 38 and 39, mounted in the bracket 6.

The gear wheels 36 and 37 mesh with a bevel gear wheel 40 which is rotatable on the shaft 8, and which is rigidly secured to the hub 13 of the rotor member.

Open air spaces are provided between the cylinders, and in such air spaces are respectively disposed fan blades 41, which preferably extend from the hub 13 to the rim 18, and which are oblique to the plane of rotation of the rotor member. Upon rotation of the latter, the blades 41 will produce a current of air which passes through the open spaces between the cylinders and in contact with and effecting cooling of the latter.

The body 1 may have in proximity to the ignition openings a water chamber 42, which effects cooling of that portion of the body, and which has connected to it a water supply pipe 43, and a water discharge pipe 44.

Each of the cylinders 14, 15, 16 and 17 may terminate in the rim portion 18 with an outwardly beveled seat in which is fitted a beveled transversely divided packing ring 45, having an arcuate outer side and having an inside diameter less than the diameter of the cylinder in which it is located, and which is adapted to be held by internal pressure exerted on its inner side against the inner periphery of the body 1, thereby providing a tight non-leaking joint between the adja-

cent cylinder and the casing body 1. The rings 45 are of the usual resilient compressible type, and when sprung into their respective seats, their expansive action and beveled peripheries also serve to force them outwardly against the body 1.

By having the cylinders provided with open outer ends arranged to be closed by the casing body 1, the use of valves is dispensed with, thus affording a simple construction, and which avoids the expense incidental to valve construction and the grinding and upkeep thereof.

In the operation of the invention, assuming that the rotor member is to revolve clockwise, as viewed in Fig. 4, fuel will be supplied through the pipe 4 to the port 2. As the rotor member is revolved in said direction, the cylinders 17, 14, 15 and 16 will consecutively pass the port 2, and when so passing, explosive charges will be consecutively drawn, by the inward movements of the pistons, into the cylinders, and these charges will be compressed, after the cylinders pass the port 2, and will be fully compressed by the outward movement of the pistons when the cylinders respectively communicate with the ignition openings 27, 28, 29 and 30.

The spark plugs 34, 31, 32 and 33 will effect consecutive ignition of the compressed charges in the different cylinders, thereby forcing the pistons inwardly consecutively. The inward movement of the pistons will effect rotation of the shaft 8 in one direction by means of the connecting rods 23, 24, 25 and 26, and the cranks with which they respectively connect. The rotation of the crank shaft 8 will, by means of the gear wheels 35, 36, 37 and 40, effect rotation of the rotor member in the opposite direction. As the crank shaft revolves in one direction and the rotor member in the opposite direction, the torque produced by the rotation of each of these members will counteract the torque produced by the rotation of the other member.

When the cylinders reach the position of the cylinder 14, as shown in Fig. 4, the pistons will have reached the inner ends of their strokes and will start outwardly, thus expelling the exploded charges into the exhaust port 3, with which the exhausting cylinder at the time will communicate. The exhaust will escape through the pipe 5.

I do not limit my invention to the structure shown and described, as modifications, within the scope of the appended claims, may be made without departing from the spirit of my invention.

What I claim is:—

1. In a rotary engine, a casing member, a member having a cylinder having an open end arranged to be closed by said casing member, said members being relatively ro-

tatable with respect to each other, and a resilient transversely divided movable packing ring fitted in said cylinder and having a bearing against said casing member and 5 at its periphery against said cylinder.

2. In a rotary engine, a casing member, a member having a cylinder having an open end arranged to be closed by said casing member, said open end having an outwardly 10 flaring seat, said members being rotatable relatively to each other, and a movable transversely divided resilient packing ring held compressed in said seat and bearing against said casing member and against 15 said seat.

3. In a rotary engine, a casing member,

having a circular inner periphery, a member having a cylinder having an open end arranged to be closed by said casing member, said cylinder at its open end having 20 an arcuate annular outwardly flaring seat, said members being rotatable relatively to each other, and a packing ring having a beveled periphery fitted to said seat and having an arcuate outer side fitting against 25 the inner periphery of said casing member, the packing ring being transversely divided, resilient, and held compressed in said seat.

In testimony whereof I have signed my name to this specification.

THOMAS E. BRALEY.
